UNITED STATES PATENT OFFICE.

BENJAMIN L. SHAFFER, OF WELDON, ILLINOIS.

FEED-TABLE FOR BALING-PRESSES.

1,097,193.

Specification of Letters Patent. Patented May 19, 1914.

Application filed April 22, 1913. Serial No. 762,622.

To all whom it may concern:

Be it known that I, BENJAMIN L. SHAFFER, citizen of the United States, residing at Weldon, in the county of DeWitt and State 5 of Illinois, have invented certain new and useful Improvements in Feed-Tables for Baling-PresSES, of which the following is a specification.

This invention relates to portable baling 10 presses, and has special reference to means for supporting the feed table.

Portable baling presses have heretofore been provided at the rear end with a laterally extending feed table hingedly connected 15 to the frame of the press at the side thereof so that material deposited upon the feed table may be delivered to the feed chamber or the baling chamber by an operator standing upon a platform also provided upon the 20 side of the press frame. These feed tables, however, have been supported by a prop extending from the table to the ground so that when it was desired to move the press from one point of operations to another point or 25 from one side of a stack to another side it was necessary to remove the prop and also remove the table before the press could be drawn to the new place of operation.

It is the object of my invention to provide 30 an improved support for the feed table whereby it will be securely held in operative position when in use and readjustment of the same will not be necessary when it is desired to move the press from place to place 35 so that the operation of the press may be continuous and uninterrupted. This object, and such other incidental objects as will appear from the following description, are attained by means such as illustrated in the 40 accompanying drawings, and the invention consists in certain novel features which will be particularly pointed out in the claims following the description.

In the drawings: Figure 1 is a side elevation of the rear end of a portable baling press showing the feed table in position thereon and supported by my improved device; Fig. 2 is a detail perspective view of the rest or support for the table removed 50 from the press; Fig. 3 is a detail view of a portion of the support.

The baling press is indicated generally at 1 and may be of any desired type, being provided with a platform 2 on its side near its 55 rear or feed end, as shown. In carrying out my invention, the feed table 3 is provided

with brackets or hooks 4 adapted to engage a longitudinal rod 5 secured upon the side of the press frame so that the table will be held with its inner end in position to discharge the hay or straw placed thereon into the press and adapted to support the table against the side of the press in a pendant position when it is not in use. At the lower portion of the press frame I secure to the 60 side thereof a rearwardly extending arm or bar 6 which is disposed horizontally and projects beyond the end of the frame below the hopper, as will be readily understood on reference to Fig. 1. This supporting arm or 65 bar 6 is braced by a strap 7 secured thereto and also secured to the press frame above the bar, the inner ends of the bar and said brace or strap being reinforced by a connecting bracket 8. To the outer end of the 70 supporting arm or bar 6, I rigidly secure a brace or rod 9 which extends upwardly and rearwardly and has its upper rear extremity rigidly secured to the corner of the frame 10 supporting the hopper of the press. To fur- 75 ther guard against twisting of the hopper under the strain placed upon the side of the same by the feed table support, I provide a long brace 11 which is bolted to the far side of the baling chamber and extends upwardly 80 and rearwardly therefrom to be secured to the far side of the frame 10, as will be readily understood. A second bar 12 is disposed at an angle to the supporting bar 6 and this second supporting bar 12 has rigidly secured 85 to one end clips 13 which are adapted to fit over the upper and lower edges of the supporting arms 6 and be secured thereto by a set-screw 14. By this construction, the lateral supporting arm 12 may be adjusted 90 more or less longitudinally of the supporting bar 6 so that the rest or support may be applied to baling presses of different dimensions and when once adjusted will be held in the set position by the screw 14 so 100 that accidental disarrangement of the structure will not occur. Should it be necessary to remove the arm 12 for any reason, the set-screw 14 may be removed and the bolt 15, by which the clips are secured to said bar, then 105 loosened so as to permit the clips to be disengaged from the rearwardly extending arm 6 without necessitating the removal of the said arm and the braces connected thereto from the press. Upon the upper side of the 110 arm or bar 12, at the outer end thereof, I secure a bracket 16 and by the same bolt 17

that secures the inner end of said bracket upon the said bar I secure a brace rod 18 thereto, the inner upper end of said brace being secured to the frame 10, as clearly shown in Fig. 1. The bracket 16 is provided between its ends with an upstanding eye or loop 19, and adjacent said loop with an upstanding finger or stop 20. A standard 21 is employed, the lower end of said standard being bent laterally, as shown at 22, and engaged in eye or loop 19 so as to constitute a pivot or journal for the standard, as will be readily understood, and to the upper end of said standard I rigidly secure 15 a head or table-engaging rod 23 having its ends upturned, as shown at 24. This rod 23 bears against the under side of the feed table 3 against the outer side of cleat or cross bar 25 thereon and the upturned ends 20 24 by engaging the sides of the feed table prevent relative lateral movement between the feed table and the support.

When the device is in use the standard 21 will rise from the bar 12 against the stop or 25 finger 20 and the cross head 23 will bear against the under side of the feed table, as above stated and as clearly shown. In this position of the parts outward movement of the standard and cross head will be prevented by the stop or finger 20 and inward movement thereof will be prevented by the cross bar 25 on the bottom of the feed table so that the table will be firmly supported in 30 position to receive the material thrown thereon and direct the same into the hopper or feed chamber of the press. When one side of the stack has been fed into the press, the team is driven around the stack without stopping the operation of the press and 35 the feeding of the material into the press continues without interruption. When it is desired to move the press to a different field or to haul the same into a shed or barn after all the material has been baled, the feed 40 table may be lifted slightly so as to permit the standard 21 to swing inwardly against the side of the press and the table will then swing toward the press so that it will be supported in a position which will permit 45 the press to be drawn through the door of the barn without requiring the removal of the feed table.

It will be readily noted that my feed table support is exceedingly simple in its construction and the arrangement of its parts 50 and may be applied to any press at a very slight cost. It will effectually hold the table in operative position and its use will effect a considerable economy in time and labor, 55 inasmuch as it will not be necessary to arrest the operation of the press in order to re-adjust the table or its support when it is necessary to move the press from one point to another in baling all the hay gathered 60 65 from a particular field.

What I claim is:—

1. The combination with a baling press, and a feed table attached to the side thereof, of a supporting arm secured to the baling press below the table, and a standard journaled upon and rising from the said supporting arm and adapted to engage the under side of the feed table. 70

2. The combination with a baling press, and a feed table attached to the side of the same, of a supporting arm secured to the baling press, a bracket secured thereto, a standard journaled in said bracket and engaging the under side of the feed table, and a stop rising from the supporting arm to 80 limit the outward movement of said standard. 75

3. The combination with a baling press, and a feed table attached to the side of the baling press, of a supporting arm, a bracket secured thereto having an upstanding finger, and a standard journaled in said bracket immediately adjacent and adapted to bear 85 against the inner side of said finger. 90

4. A device for the purpose set forth comprising a supporting arm, a bracket secured upon the said arm at the outer end thereof, said bracket being provided with a transverse eye intermediate its ends and with an upstanding finger immediately adjacent said 95 eye and between the same and the outer end of the bracket, and a standard having a laterally extending lower end journaled in said eye and resting on the supporting arm, the standard being adapted to bear against 100 the said finger. 100

5. The combination with a baling press, and a feed table attached to the side of the baling press, of a supporting arm, a standard journaled upon the said arm and rising 105 therefrom, and a cross head rigid with the upper end of said standard and adapted to engage the underside of the feed table. 110

6. The combination with a baling press, and a feed table hinged thereto and provided with a cross bar on its under side, of a supporting arm secured to the baling press, and a standard mounted upon the said arm and provided at its upper end with a cross head adapted to bear against the cross bar 115 of the feeding table. 115

7. A device for the purpose set forth comprising a bar adapted to be secured to a baling press, a brace secured to the outer end of said bar and to the outer end of the baling press, a laterally extending arm supported by said bar, and a standard mounted upon the said laterally extending arm. 120

8. A device for the purpose set forth comprising a bar adapted to be secured to a baling press, a supporting arm disposed laterally with respect to said bar, clips secured to the inner end of said arm and engaging the edges of said bar, a bracket secured upon the said bar at the outer end 125 130

thereof, and a standard journaled in said bracket.

9. A device for the purpose set forth comprising a supporting arm adapted to be connected to a baling press, a standard rising from said arm, and a cross head carried by the upper end of the standard to engage the underside of a feed table and having its ends

upturned to engage the sides of the feed table.

In testimony whereof I affix my signature in presence of two witnesses.
